UNITED STATES PATENT OFFICE.

NEWTON C. WELLS, OF LOS ANGELES, CALIFORNIA.

BUTT GAUGE.

Application filed May 5, 1924. Serial No. 711,147.

My invention relates to butt gauges and consists of the novel features herein shown, described and claimed.

The objects and advantages will appear from the drawings and specification.

The drawings illustrate the construction and operation of a butt gauge embodying the principles of my invention.

Figure 1 shows a top plan view of the butt gauge and the operation of making working lines on the edge of a door as viewed in the direction of the arrow 1 in Fig. 2.

Fig. 2 is a horizontal section on the line 2—2 of Fig. 1 and looking downwardly, thus showing the door in section and the gauge in side elevation.

Fig. 3 is a view analogous to Fig. 1 and showing the operation of scribing a depth line on the face of the door as viewed in the direction of the arrow 3 in Fig. 4.

Fig. 4 is a sectional view analogous to Fig. 2 and taken on the line 4—4 of Fig. 3 and looking in the direction indicated by the arrows and showing in elevation the opposite side of the gauge.

Fig. 5 is a view showing the use of the secondary scribe.

Fig. 6 is a bottom plan view upon an enlarged scale as indicated by the arrows 6 in Figs. 4 and 7, parts being shown in section.

Fig. 7 is a vertical cross sectional detail on the line 7—7 of Fig. 6 and right side up as indicated by the line 7—7 in Fig. 1, with the door omitted.

Fig. 8 is a fragmentary perspective of the edge of a door and showing the working lines for applying a hinge to the door, the lines being made by the use of my gauge.

The details of the construction and operation of the butt gauge shown in the drawings as follows:

The central main frame 1 consists of a flat top 2 and parallel sides 3 and 4 extending downwardly at right angles from the edges of the top 2. The central longitudinal marking member 5 is bent downwardly from the forward end of the top 2 in a plane at right angles to the sides 3 and 4 and has a marking edge 6 (Fig. 7) extending slightly below the edges of the sides 3 and 4. The top 2, the sides 3 and 4, the marking member 5 and the edge 6, are all formed integral from heavy sheet metal and the marking member 5 extends entirely across the sheet of metal and the sides 3 and 4 are bent inwardly from

the same edges that form the ends of the marking member, thus making curves 7 and 8 connecting the sides 3 and 4 to the ends of the marking member.

The abutment member 9 (Fig. 7) comprises 60 a central bottom plate 10 fitting against the lower edges of the sides 3 and 4 with lugs 11, 12, 13 and 14 turned upwardly at the corners and fitting inside of the sides 3 and 4 so that the plate will slide back and forth. 65 The abutment 15 is bent downwardly from the forward edge of the plate 10 in a plane parallel with the marking member 5. An adjusting screw 16 is mounted through a longitudinal slot 17 formed in the top 2 and 70 screw threaded through the plate 10, and has a bearing head 18 engaging the top 2 so that by loosening the screw 16 the abutment 15 may be moved towards or away from the marking member 5. 75

The primary scribe 19 is formed upon the forward end of a flat bar 20 which slides through an opening in the marking member 5 and fits upwardly against the top 2, and an adjusting screw 21 is inserted through a 80 slot 22 in the top 2 and tapped through the bar 20 so that by manipulating the screw 21 the scribe 19 may be moved to or from the marking member 5, and when the scribe 19 is to be used the forward face of the marking member 5 forms a guide or an abutment with relation to which the scribed 19 is adjusted. The edge of the scribe 19 is parallel with the forward face of the marking member 5 and some distance above 85 the marking edge 6 so as to be out of the way when the marking edge 6 is used.

The parallel bars 23 and 24 are slidably mounted through apertures in the sides 3 and 4. The transverse marking member assemblies 25 and 26 are mounted upon the ends of the bars 23 and 24, one on each side of the main frame 1.

The details of the transverse marking assembly 25 are as follows:

A piece of heavy sheet metal is bent to form the top 27 (Fig. 6) and the sides 28 and 29, and the clamping screw 30 is mounted in the channel against the lower face of the top 27 between the sides 28 and 29 and 105 has a transverse slot forming a clamping shoulder 31 and a screw threaded outer end 32. The bar 23 is slidably mounted through the sides 28 and 29 and has a retaining head 33 upon its outer end. The bar 24 is slidably 110

- mounted through the sides 28 and 29 and in the notch against the shoulder 31, and has a retaining head 34 upon its outer end. A washer 35 is mounted upon the screw threaded end 32 against the ends of the top 27 and sides 28 and 29 and an adjusting nut 36 is mounted upon the screw threaded end 32 against the washer so that by loosening the nut 36 the member 25 may be moved upon the bar 24, and by tightening the screw 36 the shoulder 31 will engage the bar 24 and hold the assembly 25 rigid upon the bar. The side 29 is cut short at its forward end and the top 27 is cut upon the line 37 so that the line 37 will clear the line 7 and the forward end of the side 28 extends in the plane of the marking member 5, and the end face 38 of the side 28 serves as a locator for the gauge in some of the operations.
- 10 The details of the transverse marking assembly 26 are as follows:
- A piece of heavy sheet metal is bent to form the top 39 and the sides 40 and 41. The clamping screw 42 fits in the channel 25 against the lower face of the top 39 between the sides 40 and 41 and has a slot forming a shoulder 43. The bar 23 extends loosely through the sides 40 and 41 and through the slot and against the shoulder 43. A secondary scribe 44 is formed on the outer end of the bar 23. A second clearance slot 45 is formed across the screw 42 and the bar 24 extends through the sides 40 and 41 and loosely through the clearance slot 45, and is secured rigidly in place by a headed pintle 46 on the outer end and in the side 41. A washer 47 fits against the ends of the top 39 and sides 40 and 41 and a nut 48 is screw seated upon the screw 42 against the washer 47 so that by loosening the nut 48 the assembly 26 may be moved upon the bar 23 to adjust the distance between the edge of the scribe 44 and the outer face of the side 41. When the secondary scribe is to be used, the side 41 serves as an abutment. By manipulating the nuts 36 and 48 the assemblies 25 and 26 may be adjusted to and from each other. The side 40 is cut short at its forward end and the top 39 is cut on the line 49 to clear the line 8, and the forward end 50 of the side 41 extends in the plane of the marking member 5 to the same extent as the edge 38, and serves as a locator or as bearings for some of the operations.
- 55 When the assemblies 25 and 26 are bearing upon a door or the like, the central frame 1 and all the parts carried thereby may be moved back and forth upon the bars 23 and 24 to the limit of the space between the assemblies 25 and 26.
- 60 The sharp edges 51 and 52 of the sides 28 and 41 extend below the edges of the sides 29 and 40 and are beveled to form markers and are in the same level as the edge of the marking member 5.

In handling the gauge for adjustment and the like, the faces shown in Figs. 1, 3 and 5 form the top of the gauge.

Referring to Figs. 1 and 2, the gauge has been adjusted to fit a hinge leaf which is to be applied to the door 53 (Fig. 8) and the gauge is applied to the door with the abutment 15 against a side face of the door and with the marking edges 6, 51 and 52 against the edge face of the door, and the gauge may be tapped with a hammer, one blow of the hammer hitting the marking assembly 26 and making the transverse mark 54, and another blow hitting the marking assembly 25 and making the transverse mark 55. A third blow of the hammer will hit the top 2 near the marking member 5 and make a part of the longitudinal line 56. The main frame 1 should be moved against the assembly 26 to make the upper part of the line 56 and against the assembly 25 and making the lower part of the line 56.

Referring to Figs. 3 and 4, the scribe 19 is adjusted to the depth of the hinge member and the gauge is turned to bring the marking member 5 against the edge face of the door and the scribe 19 against the side face of the door, and the locators 38 and 50 are pressed against the edge face of the door at the marks 54 and 55 and the assemblies 25 and 26 pressed against the edge of the door while the main frame 1 is reciprocated upon the bars 23 and 24 with the marking member 5 serving as an abutment, and the scribe 19 bearing upon the face of the door to make a part of the line 57. This gives a straight start in making the line, and the line may be finished by any suitable manipulation or left unfinished.

Referring to Fig. 5, the secondary scribe 44 has been adjusted relative to the outer face of the side 41 of the assembly 26 to make a line 58 at the center of the edge of the door 59 to form a starting point from which to lay off the lock mortise.

110 Various other operations will be obvious to a person familiar with placing hinges and locks upon doors and the like.

Various changes may be made without departing from the spirit of my invention as claimed.

I claim:

1. In a butt gauge, a main frame comprising a flat top portion and parallel side portions extending downwardly at right angles from the edges of the top portion, the forward end of the top portion being laterally expanded, and a marking member extending downwardly from said forward end at right angles to the sides and longer than the width of the main portion of the top.

2. In a butt gauge, a main frame comprising a flat top portion having a longitudinal slot and parallel side portions extending downwardly at right angles from the edges

of the top portion, the forward end of the top portion being laterally expanded, a marking member extending downwardly from said forward end at right angles to the 5 sides and longer than the width of the main portion of the top, and an abutment member comprising a central bottom plate fitting against the lower edges of the sides and having a screw-threaded aperture, an abutment 10 extending downwardly from the forward edge of the bottom plate in a plane parallel with the marking member and an adjusting screw mounted through the longitudinal slot formed in the top and the screw 15 threaded aperture in the bottom plate so that the abutment may be moved toward or away from the marking member.

3. In a butt gauge, a main frame comprising a flat top portion with a slot therein, and parallel side portions extending downwardly at right angles from the edges of the top portion, the forward end of the top portion being laterally expanded, a marking member extending downwardly 20 from said forward end at right angles to the sides and longer than the width of the

main portion of the top and having an opening at the end of the marking member, a flat bar extending through the opening and having a scribe formed on one end and having a screw threaded aperture adjacent the other end and an adjusting screw fitting through the said slot and screw threaded aperture in the bar whereby the scribe may be adjusted with reference to the marking member. 30

4. In a butt gauge, a main frame, parallel bars slidably mounted through the main frame, side marking assemblies adjustably mounted upon the parallel bars, one on each 40 side of the frame, each of said assemblies comprising a top, sides extending downwardly from the top and forming therewith a channel, an adjusting screw mounted in the channel and having a slot, said bars extending through the sides, one of the bars 45 extending through the slot in the adjusting screw, and a nut upon the adjusting screw for gripping the bar in the slot.

In testimony whereof I have signed my 50 name to this specification.

NEWTON C. WELLS.
